Primary Examiner — Shawn T Gingrich*Assistant Examiner* — Bryan Nolan Melvin(74) *Attorney, Agent, or Firm* — Meunier Carlin & Curfman LLC(57) **CLAIM**

The ornamental design for equipment for distribution of electric power, as shown and described.

DESCRIPTION

FIG. 1 is a perspective view of the equipment for distribution of electric power, showing our new design;

FIG. 2 is a front view thereof;

FIG. 3 is a right side view thereof;

FIG. 4 is a top plan view thereof;

FIG. 5 is a rear view thereof;

FIG. 6 is a left side view thereof; and,

FIG. 7 is a bottom plan view thereof.

1 Claim, 7 Drawing Sheets(56)
